SECOND OF TIME RANGE FINDER

Original Filed April 4, 1926

UNITED STATES PATENT OFFICE

WILLIAM Q. KENNEDY, OF NEW YORK, N. Y.

SECOND OF TIME RANGE FINDER

Original application filed April 4, 1926, Serial No. 101,867. Divided and this application filed July 3, 1928. Serial No. 290,234.

This invention relates to ordnance and more particularly to range finders used in conjunction therewith.

One object of the invention is to provide an improved range finder permitting the gun to be sighted upon a target with a minimum of time and labor and yet with a high degree of accuracy.

Another object of the invention is the provision of an improved range finder which is correlated with the known muzzle velocity of a projectile fired from a gun wherewith the range finder is used, the latter being calibrated according to suitable time intervals and having deflection markings permitting the operator not only to rapidly determine the range of the target, but also by observing the deflections produced by the image of a moving target to allow for the velocity thereof, and accordingly to assure an accurate firing of the gun.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawings:

Figure 1 is a fragmentary view showing the range finder and a portion of a gun whereon it is mounted.

Fig. 2 is an enlarged sectional view in elevation of the range finder.

Fig. 3 is a sectional view approximately on the line 3-3 of Fig. 2.

Fig. 4 is a reduced sectional view approximately on the line 4-4 of Fig. 3.

Figs. 5 and 6 are diagrammatic views illustrating the method of operation of the instrument.

The advantages of the invention as here outlined are best realized when all of its features and instrumentalities are combined in one and the same structure, but, useful de-

vices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

My improved range finder is particularly adapted for use in conjunction with my Self-centered, non-sighted, second of time gun disclosed in Patent No. 1,723,623, August 6, 1929, and of which application this is a division.

The range finder 85 is secured to the trunnion 65 of the muzzle of the gun 66 so as to lie disposed beneath the carriage 39 of the gun and nevertheless to move directly with the gun. The range finder is thus positioned beneath the gun and in front of the same and mounted for longitudinal movement by guide means 86.

The range finder is sighted on the target and the range is obtained by bringing the image to a focus. By suitable calibration of the instrument, the elevation of the gun is obtainable directly from the range. Means are likewise provided to allow for the movement of the target while the projectile is traveling through the air to strike it.

The range finder includes a casing 87 within which is slidably fitted a telescopic chamber or tube 88 which contains various focusing lenses. Guide means 89 are provided to insure of absolutely uniform movement of the focusing tube. A plurality of racks 90 are mounted on the side of the focusing tube to mesh with pinions 91 on shaft 92 which is rotated by drum 93, whereby the focal length of the instrument can be adjusted. The image is brought to a focus on a sheet 94 of translucent unbreakable material, such, for example, as celluloid, which is disposed across the instrument in perpendicular relation to the axis of the instrument, and the movement of the focusing tube is toward or away from the plate.

The instrument is accurately calibrated, as at a dial 95 adjacent to drum 93, so that

when the target is properly focused on the plate 94 by movement of the drum and corresponding movement of the dial and focusing tube, the range may be directly read upon the dial. However, since the muzzle velocity 5 of the gun is known, that being always ascertained by proper tests beforehand, the time in number of seconds that it would require for the projectile to reach the target can be 10 easily obtained. This time is marked on the dial opposite to the figures for different distances or ranges.

A mirror 96 is mounted at the base of the instrument to pivot about an axis at 97. 15 Props 98 are fixed to a shaft 99 to be rotatable therewith as by manipulation of a drum 100. Upward or downward movement of the props causes a similar movement of the mirror, the mirror being retained 20 in engagement with the props by brackets 96a. Means are provided operative between the drum 100 and the body of the instrument to lock the drum after adjustment. As a simple 25 illustration of conventional locking means, I show the thimble 100 as being of hollow form, and connected to shaft 99 by a spline 101. A locking pin 102 engages said body through the reaction of a spring 103 which continually forces the drum toward the body. 30 A window 104 is provided in the line of sight, so that when the mirror is moved in clockwise direction away from the axis of the instrument, a view may be obtained through window 104 directly through the instrument. 35 A window 105 is likewise provided through which the operation of the instrument is observed continuously and readings are taken. On the focusing plate 94 are various permanent markings, including a central line of sight 106, and a plurality of transverse lines 107 at right angles thereto beginning with a zero line at point 108 which is the axial line of sight, the other transverse lines being marked 10,000, 20,000, and 30,000. An 40 image of these lines and the markings appears on the mirror 96 as shown at 106a, 107a and 108a.

The elevation of the gun that is necessary to hit a particular target is obtained by 45 means of the lines and markings on the focusing plate and their images on the mirror. It is assumed that the range is to be determined in seconds of time as stated hereinbefore. Bearing in mind that the mirror is retained 50 always at a fixed predetermined angle of say 45° with the axis of the instrument, the gun is elevated until the image appears on the mirror as near to the corresponding range as may be obtained. Further focusing may or 55 may not be resorted to as desired. Lines 107 being calibrated, the gun is at the right elevation for firing at the target.

As a preliminary step, however, to placing the gun in position for firing, readings 60 are made to determine the necessary allow-

ance for the movement of the target while the projectile travels toward it. For this purpose a screw 109 is provided, threaded right hand at one side of the axial plane of the instrument and left hand and of the 70 same pitch at the other side thereof. The screw is rotated by thumbpiece 110. Pointers or tangent sights 111 are provided, one for each side of the instrument with respect to said axial plane, the pointers having hubs 112 threaded on corresponding portions of the screw. The pointers include the extending or indicating members 113 which are 75 pivotally connected to the shanks of the pointers at 114.

A spring 115 tends to move member 113 in counterclockwise direction. A sleeve 116 is mounted coaxially with screw 109 and is rotatable independently of the screw, by thumbpiece 116a. Member 110 may have 80 suitable marks along its edge whereby the deflection of the pointers from the central longitudinal plane of the instrument can be noted. The sleeve is slotted longitudinally at 116b to permit of sliding movement of 85 the pointers therealong, but the sleeve retains the pointer at a fixed inclination with respect to the focusing plate, the spring 115 cooperating to keep the pointer in snug contact with the focusing plate. This feature is 90 a mere detail of convenience, and is intended merely to permit the end of the pointer to be adjusted or moved in a direction transverse to screw 109 according as the image is nearer or further from said screw. A second-of-time clock 117 is provided in conjunction with which the pointers are operated. The instrument is in every case so manipulated as to cause the image to move across the mirror horizontally. If the gun is being aimed upon 95 a flying machine, for instance, the flying machine will sooner or later move in such relation to the gun that the image produced will move horizontally on the mirror. It is preferable to take observations and make adjustments at such time. The pointers or tangent sights will be understood to cast shadows on 100 the mirror which follow the image as the pointers are moved in accordance with the movement of the image. The movement of 105 the pointers from the central longitudinal plane of the instrument is exactly equal.

Let us assume that the axis of the gun is represented by line A X, T being a target, L a lens in the range finder, and I an image 110 of the target. The range of the target has been obtained as described hereinbefore, and likewise the time corresponding to the range. The target travels to the position at T1, and the image moves correspondingly to I1. A 115 period of time corresponding to the range of the target is allowed to elapse while the image moves from X to I1, the target moving correspondingly from A to T1, and the deflection is noted. The gun is now traversed 120 125 130

so that the image moves back to the opposite side of the line A X, i. e., it will appear again at I, or at such other point as corresponds with the pointer at this side of the instrument. If the gun is now fired, the target will travel from T to A, in the time that the projectile moves from the gun to A. The gun will, of course, have been properly elevated as described hereinbefore. The second of time clock 117 is used conjunctively to aid in the precise firing of the gun.

I claim:

1. In a range finder, the combination with focusing means for finding the range of a target, said focusing means including a translucent non-breakable focusing plate, of means including a reflector to receive an image of the target, from the focusing plate marks being provided on said focusing plate reading in target ranges, the range finder being secured to a gun at a pivot intermediate the ends of the barrel of the gun to pivot therewith, whereby the elevation of the gun can be obtained by elevating the same and the range finder until the image of the target registers with the mark corresponding to the range of the target.

2. In a range finder adapted for use with a gun, the combination with focusing means for finding the range of a target, of an unbreakable focusing plate to receive an image of the target, marks on the plate and means coacting therewith to indicate the range in units of time, a plurality of tangent sight pointers, a screw co-operating with the pointers to move the same simultaneously and equally from a central longitudinal plane of the instrument, the deflection of the image being measured from the said plane for a period of time of travel of the target corresponding to the time necessary for a projectile to reach the target, the range finder being adapted to be secured to the gun at the pivot thereof whereby the gun and range finder may be traversed as a unit until the image is on the opposite side of said plane and at the other pointer, the gun being then fired.

3. In a range finder adapted to be mounted for movement with a gun at the pivot thereof, the combination of a celluloid plate adapted to receive an image of a target, means to focus the image, and markings associated with said means and calibrated in target ranges seconds of time, whereby the elevation of the gun may be obtained by elevating the gun and range finder until the image is associated with a mark corresponding to the range of the target, and a stop clock for the purpose set forth.

4. In a range finder adapted to be mounted for movement with a gun, the combination of a calibrated unbreakable translucent plate to receive an image of a target, means to focus the image on the plate, a plurality of tangent

sight pointers, and means co-operating with the pointers to move the same simultaneously and equally from the central longitudinal plane of the instrument, calibrated means reading in seconds of time and coacting with the focusing means, a stop clock co-ordinated with the said calibrated means, the deflection of the image being measured from said plane after the image has moved from said plane for a period of time corresponding to the time necessary for a projectile fired from the gun to reach the target, the gun and range finder being then traversed until the image appears on the opposite side of said plane and at the corresponding pointer, the gun being then fired.

5. The method of manipulating a gun to make allowance for the travel of the target while a projectile moves toward the target, which consists in focusing an image thereof and directly finding in one operation the time necessary for a projectile to strike the target according to the muzzle velocity of the gun, then obtaining a deflection after allowing the target to travel for said period of time, then traversing said gun forward of the target until the same deflection is obtained and the target is in such position relative to the gun that the projectile will strike the target after traveling for a period of time as aforesaid.

6. In a range finder adapted to be mounted on the pivot of a gun for movement therewith, the combination of means to focus and receive an image of a target, tangent sight pointers, and means to move the pointers simultaneously with respect to a fixed plane, the pointer being associated with the image receiving means in such manner that the movement of the image for a predetermined length of time can be measured.

7. The combination as in claim 6 wherein a focusing plate of translucent celluloid material is provided along which the pointers are movable, a mirror being likewise provided to receive the image that has been focused on said plate, the shadow of the pointer being adapted to follow the image in the mirror thus indicating coincidence between one of the pointers and the image on the focusing plate.

8. In a range finder as set forth in claim 3, in which other means are provided whereby the deflection of the image may be measured for a period of time of travel of the target corresponding to the time necessary for a projectile to reach the target, the range finder being adapted to be traversed with the gun until the image is set at a predetermined point to cause the projectile to strike the target.

9. In a range finder adapted to be mounted for movement with a gun, the combination of focusing means, a translucent celluloid plate to receive an image of a target, tangent sight

pointers, and means to move the pointers simultaneously and equally with respect to a fixed central plane, the pointers being associated with the image receiving means in such manner that the movement of the image for a predetermined length of time can be measured, the pointers being movable along the said plate, a mirror being likewise provided to receive the image that has been focused on said plate, the shadow of the pointer being adapted to follow the image in the mirror thus indicating coincidence between the pointer and the image on the focusing plate, there being markings on the focusing plate corresponding to the ranges of the target, the range finder and gun being elevated until the image coincides with a proper range mark, said pointers being adjustable in a direction transverse to its path of movement aforesaid to follow the image regardless of the line of movement thereof along the focusing plate due to elevation of the range finder, means calibrated in seconds of time corresponding to the ranges, and a second of time stop clock, for the purpose set forth.

25 In testimony whereof I affix my signature.
WILLIAM Q. KENNEDY.
